TENT CONSTRUCTION

Benjamin Clearmont, Fort Worth, Tex.

Application September 2, 1938, Serial No. 228,184

6 Claims. (Cl. 135—15)

This invention relates to tents and it has particular reference to a tent construction adapted to be readily erected with the maximum of ease and alacrity, requiring a minimum of effort in its handling and possessing many novel and salient features conducive to exceptional portability and application.

Another object of the invention resides in the provision of a tent construction embodying few adjustable parts yet durable and capable of resisting the elements, affording desirable housing facilities for such purposes as portable tabernacles, circus and show tents, relief projects, and many other usages for which such portable structures may be employed.

Yet another object of the invention is manifest in the provision of a structure requiring little bracing apparatus, such as guy ropes or wires, thereby eliminating much of the usual paraphernalia required in such structures and which create an undesirable hazard from the standpoint of safety as well as the requisite of additional labor and expense in erection and maintenance.

A specific object of the invention resides in the provision of an arrangement of elements permitting the normal contraction and expansion of the canvas top, usually prevalent due to the changing of atmospheric conditions, without necessitating the manual adjustment of guys conventionally arranged in spaced relationship along each side of the tent and secured by stakes to the ground, the novel construction herein described being such as to maintain the canvas taut under varying conditions unattended by any human agency other than to properly adjust the operative elements when the structure is erected.

Broadly, the invention seeks to comprehend the provision of a tent construction of the character described which is capable of assembly and erection by a single individual, or in the case of exceptionally large structures, with a minimum of man power and affording an economical as well as a practical portable housing unit.

While the foregoing objects are paramount, other and lesser objects will become manifest as the description proceeds taken in connection with the appended drawing wherein:

Figure 1 is a perspective view of a tent construction showing the weighted levers arranged along the sides thereof and operatively connected to the eave-pole of the structure.

Figure 2 is a fragmentary perspective illustration of one end of one of the eave-poles showing the manner in which a section of the top canvas is attached to the eave-pole and also showing the

manner in which the weighted lever is applied, the said lever being utilized as a wrench.

Figure 3 is a lateral cross sectional illustration of the structure showing the frame work thereof and the top canvas extending downwardly and around the eave-poles on each side and showing the weighted levers retaining the canvas stretched across the ridge pole. The weighted levers are also shown in dotted lines in the uppermost portion.

Figure 4 is a fragmentary cross sectional illustration of one of the journal assemblies for the eave-poles and showing, in cross section, the application of the weighted levers which, as shown in dotted lines, may be also utilized as wrenches, and

Figure 5 is a fragmentary plan view of a section of the frame work illustrating the manner in which the same is assembled.

Accordingly, therefore, the invention comprises primarily a frame work which consists of a pair of upright members 1 arranged on each side of the longitudinal axis of the assembly, as shown in Figure 3, and these members are braced by angular supports 2 which are connected at their uppermost ends to a cross beam 3 whose ends are also supported at a by the vertical supports 4. The members 1 are attached to the cross member 3 at a point a short distance inwardly from the outer ends of the cross member 3.

A ridge pole 4 is supported centrally of the assembly by an upright beam 5 which is attached at its lowermost end to the cross member 3 at the conjunction b of the two angular supports 2. The vertical element 5 is also reinforced by angular braces 6 which extend upwardly from the cross member 3. Extending along both ends of the cross member 3 are provided longitudinal rails 7 which are preferably positioned at an angle with respect to a vertical plane and are thus secured, through the medium of special brackets 8, to the ends of the cross member 3. A detail of this structure is illustrated in Figure 5.

The superstructure, which is described, is laterally supported by braces 9 and 10 extending downwardly and outwardly at an angle from the supports 1, as illustrated in Figure 3, and additionally strengthened by auxiliary braces 11 and 12 extending between the supports 1 and the members 9 and 10 and connected to the latter through the medium of plates 13 and 14 which are preferably of metal, or the like.

The outer ends of the braces 9 and 10 are supported by wall posts 15 and 16 which are prop-

erly spaced along the length of the structure as is the case also of the frame work which has just been described. The lateral braces 9 and 10 overreach the upper ends of the wall posts 15 5 and 16 sufficiently to accommodate at their outer ends a pair of bearings 17, as shown in cross section in Figure 4, adapted to receive the spindles 18 in the ends of eave-poles 9 which are so journaled as to permit their rotation, the purpose 10 of which will be presently described.

Sections of canvas 20 are arranged across the ridge pole 4 and their ends secured to and rolled upon their eave-poles 19 in a manner shown in Figure 2. The canvas may be secured by any 15 means, such as by tacking, or the like, to eave-poles 19 and it is preferable to so secure these elements as to enable their being disconnected at will when it is desirable to transport the assembly. When the structure is erected in the manner 20 just described arms 21, having rectangular opening at one end thereof adapted to surround the rectangular banded ends c of the eave-poles 19, are arranged over these members, in the manner shown in Figures 2 and 4, and operated as a 25 wrench to tighten the canvas on the eave-poles 19, by rotating the latter whereupon a weight 22, suspended by a chain or a cable 23, is attached to the outer ends of the arms 21 at d which will retain the canvas 20 tautly across the ridge pole 4 and over the longitudinally extending rails 1 30 intermediate the ridge pole 4 and the eave-pole 19 on each side of the structure. In reference to Figure 4, it will be noted that the arms 21 may be slipped off the ends of the ridge pole 19, 35 as illustrated in dotted lines, and rotated to a position where, when these members are again placed over the ends c of the ridge pole 9, a new hold may be attained.

Each section of the canvas 20 may be joined 40 together at the communicating ends of the poles 19 by such means as snaps and rings 24, or similar device, and a small flap (not shown) may be arranged over the substantially rectangular opening e resulting from the space required by the 45 joining together of the eave poles 19 and will allow the arms 21 to be properly connected thereto, as illustrated in Figure 2.

As previously pointed out, a specific object of 50 the invention herein described resides in the provision of a structure which can be readily erected with a minimum of effort and it is therefore preferable to join the various braces and supports together by means of pins f in order to expedite the assembly. In practice it has been learned 55 that after the structure has been properly erected it remains rigid and therefore properly retains in a unit by reasonably cross fitting pins. Bolts having nuts threaded thereupon may be employed if such is considered expedient but the use of 60 such equipment is believed unnecessary in view of the fact that one of the principal objects of the invention is to provide a tent structure requiring a minimum of time and effort in its assembly.

After the supporting frame work has been assembled, these assemblies are erected and secured together by the ridge pole 4 and the longitudinal rails 1. The eave-poles 19, having the pins f 65 extending from the ends thereof, as shown in Figure 4, are placed in position so that the spindles 18 are extending into the bearings 17 secured to each side of the laterally extending braces 9 and 10 and on the outer ends thereof. The arms 21, however, must be slipped over the bend at 70 the ends c of the poles 19 before the spindles 18 are

inserted in the bearings 17 in the manner just described. The arms 21 can then be urged toward the ends of the poles 19 and disengaged therefrom, as shown in dotted lines in Figure 4, so that these members can be rotated to any desired position to properly rotate the poles 19 and therefore exert sufficient tension on the canvas 20 to retain the same in its stretched condition across the ridge pole and the rails 1. After the arms 21 are properly adjusted and the weights 22 attached, the canvas 20 may contract and expand without undue strain, the degree of such contraction and expansion being dependent upon atmospheric conditions. The assembly may be braced on each end by guys 25 which may be attached to stakes of a conventional character driven into the ground, as illustrated in Figure 1.

Manifestly, the structure shown is capable of certain changes and modifications by those skilled in the art and such changes and modifications which may be resorted to from time to time and which may be considered as coming within the spirit and intent of the invention may also be considered as falling within the scope of the appended claims.

What is claimed is:

1. In a tent construction, the combination of a sheet of canvas, a ridge pole and rotatably mounted eave-poles, a supporting frame work for the said ridge pole and the said eave-pole, the 30 said canvas arranged over the said ridge pole and secured on each side thereof to the said eave-pole and weighted levers fixedly attached to the said eave-pole whereby the latter may rotate under the normal contraction and expansion of 35 the said canvas.

2. In a tent construction, the combination of a canvas fly, a ridge pole, a pair of eave-poles and a supporting frame work for the said ridge pole and the said eave-poles, the said eave-poles 40 rotatably supported by the said frame work, the said canvas extending over the said ridge pole and attached on each side thereof to the said eave-poles and yieldable means fixedly attached to the said eave-poles for restrictedly rotating the 45 said poles to stretch the said canvas.

3. In a tent construction, the combination of a tent fly, a ridge pole and rotating eave-poles, a supporting frame work for the said canvas and the said poles, the said canvas secured to the said 50 eave-poles and rolled thereupon, yieldable means secured to each of the said eave-poles rotating the latter and stretching the said canvas.

4. In combination, a tent construction comprising a canvas fly, a ridge pole and rotating eave-poles, a supporting frame work for the said poles and the said canvas, the said canvas secured to and around the said eave-poles on each side of the said supporting frame work, and oscillating means secured to each of the said eave- 60 poles exerting tension on the said canvas.

5. A tent construction comprising a frame, a canvas over the frame, eave-poles rotatably mounted on the said frame and secured to edges of the said canvas whereby the latter is rolled 65 thereupon, and means attached to the said rotatable eave-poles restrictedly rotating the said poles and yieldably retaining the canvas taut over the said frame.

6. A tent construction comprising a frame, 70 eave-poles rotatably mounted on the said frame, canvas attached to the said eave-poles and extending over the said frame, and weighted levers laterally extending from the said poles.

BENJAMIN CLEARMONT. 75
